(57) **CLAIM**

The ornamental design for a nightly dose packet storage set as shown and described.

DESCRIPTION

FIG. 1 is a breakout, isometric view of a nightly dose packet storage set showing the new design, comprising four containers, each with seven nightly dose packets, and a receptacle with a mixing cup and two nightly dose packets;

FIG. 2 is a top, isometric view of the nightly dose packet storage set shown in an alternate configuration;

FIG. 3 is a top plan view thereof;

FIG. 4 is a top, isometric view of the nightly dose packet of the nightly dose packet storage set, shown separately to show aspects of the design that are not visible when combined;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof;

FIG. 10 is a bottom plan view thereof;

FIG. 11 is a top, isometric view of a container of the nightly dose packet storage set, shown separately to show aspects of the design that are not visible when combined;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof;

FIG. 18 is a top, isometric view of seven of the nightly dose packets in one of the containers of the nightly dose packet storage set, shown separately to show aspects of the design that are not visible when combined;

FIG. 19 is a front elevational view thereof;

FIG. 20 is a rear elevational view thereof;

FIG. 21 is a left side elevational view thereof;

FIG. 22 is a right side elevational view thereof;

FIG. 23 is a top plan view thereof;

FIG. 24 is a bottom plan view thereof;

FIG. 25 is a top, isometric view of the mixing cup of the nightly dose packet storage set, shown separately to show aspects of the design that are not visible when combined;

FIG. 26 is a front elevational view thereof;

FIG. 27 is a rear elevational view thereof;

FIG. 28 is a right side elevational view thereof;

FIG. 29 is a left side elevational view thereof;

FIG. 30 is a top plan view thereof;

FIG. 31 is a bottom plan view thereof;

FIG. 32 is a bottom, isometric view thereof;

FIG. 33 is a top, isometric view of the receptacle of the nightly dose packet storage set, shown separately to show aspects of the design that are not visible when combined;

FIG. 34 is a front elevational view thereof;

FIG. 35 is a rear elevational view thereof;

FIG. 36 is a left side elevational view thereof;

FIG. 37 is a right side elevational view thereof;

FIG. 38 is a top plan view thereof;

FIG. 39 is a bottom plan view thereof;

FIG. 40 is a top, isometric view of the mixing cup and two nightly dose packets in the receptacle of the nightly dose

packet storage set, shown separately to show aspects of the design that are not visible when combined;

FIG. 41 is a front elevational view thereof;

FIG. 42 is a rear elevational view thereof;

FIG. 43 is a left side elevational view thereof;

FIG. 44 is a right side elevational view thereof;

FIG. 45 is a top plan view thereof; and,

FIG. 46 is a bottom plan view thereof.

The broken lines depict portions of the nightly dose packet storage set that form no part of the claimed design.
